UNITED STATES PATENT OFFICE

153,102

DESIGN FOR A PIPE AND TUBING BENDER

John D. Benfield, Detroit, Mich.

Application December 7, 1946, Serial No. 135,331

Term of patent 14 years

(Cl. D54—13)

To all whom it may concern:

Be it known that I, John D. Benfield, a citizen of the United States, residing at Detroit, in the county of Wayne and State of Michigan, have invented a new, original, and ornamental Design for Pipe and Tubing Bender, of which the following is a specification, reference being had to the accompanying drawing, forming a part thereof, wherein:

Fig. 1 is a side elevational view of the pipe and tubing bender showing my new design.

Fig. 2 is a top plan view taken along the line 2—2 of Fig. 1, looking in the direction of the arrows.

Fig. 3 is a right end elevational view taken along the line 3—3 of Fig. 1, looking in the direction of the arrows; and

Fig. 4 is a left end elevational view taken along the line 4—4 of Fig. 1, looking in the direction of the arrows.

I claim:

The ornamental design for a pipe and tubing bender, as shown.

JOHN D. BENFIELD.
